UNITED STATES PATENT OFFICE.

CHARLES H. MELSON, OF NORFOLK, VIRGINIA, ASSIGNOR TO B. F. BOLSOM,
OF SAME PLACE.

ANIMAL-TRAP.

SPECIFICATION forming part of Letters Patent No. 240,747, dated April 26, 1881.

Application filed January 29, 1881. (No model.)

To all whom it may concern:

Be it known that I, CHARLES H. MELSON, a citizen of the United States, resident at Norfolk, in the county of Norfolk and State of Virginia, have invented certain new and useful Improvements in Animal-Traps; and I do hereby declare the following to be a full, clear, and exact description of the invention, such as will enable others skilled in the art 5 to which it appertains to make and use the same, reference being had to the accompanying drawings, and to letters or figures of reference marked thereon, which form a part of this specification.

15 Figure 1 is a vertical sectional view of a machine embodying my improvements; and Fig. 2 is a plan view of the same, partially in section.

20 This invention relates to mole-traps; and it consists in the construction hereinafter described, and particularly pointed out in the claims.

25 In the drawings hereto annexed, A is a frame made as a quadrant, having legs B B, base-bars C C, and curved connecting-bar D, having a slot, d, extending from the lower edge, a, nearly to the upper end of said curved bar.

30 On the inside of the base bars or cheeks C are made the bosses e e, having the depressions e' e', in which are pivoted the pintles e e of the trigger E. This consists of an arm, F, which extends upward and projects through slot d, having a thumb-piece, f, outside of said slot, and, extending downward, has pivoted 35 to its end f' an arm, G, having a notch, g, in its lower surface and a flat head, g'.

40 H is a metal plate conforming to the shape of the upper front end, I, of arm F, and having in its rear face the countersinks h h, and 45 running from these through said plate the holes n n.

KK are the piercers, curved as shown, and

having the heads k k, p, and l, and holes in plate H and head or end I. M is a washer, and N a screw.

45 P P are strong spiral springs, which encircle the bosses e and pintles e, and are made fast at one end to said pintles, and at the other to the base bars or cheeks C C.

R is a bar, which connects the cheeks C C on 50 the under side some distance in front of the bosses e e, and S is a brace, located as shown.

55 The piercers K K are slipped through holes n n until their heads k k rest in the countersinks h h, when plate H is screwed to end or head I by screw N, with washer M between, the position of the piercers being such that they curve downward from arm F.

The trap is placed over the mole-track, with the base-bars C C resting with their edges t t 60 on the ground. The arm F is drawn back by thumb-piece f, which shoves the trigger G forward until its notch g is made to catch on bar R, when the trap is set. As the mole travels along, his back, striking the head g', releases 65 the trigger G and the springs P P throw the bar F down and the piercers K K impale the animal through the back.

What I claim is—

1. Bar F, having thumb-piece f, and pintles e e, trigger G, having notch g, in combination 70 with base-bars C C, having bosses e e, with depressions e' e', bar R, and springs P P, substantially as set forth.

2. The pivoted bar carrying the piercers, in 75 combination with a trigger pivoted to its lower end, and a bar for holding the trigger, substantially as described.

In testimony whereof I affix my signature in presence of two witnesses.

CHARLES H. MELSON.
